(57) **CLAIM**

The ornamental design for a laundry sink with mini washing machine, as shown and described.

DESCRIPTION

1. Laundry sink with mini washing machine

1.1 : Perspective

1.2 : Front

1.3 : Back

1.4 : Left

1.5 : Right

1.6 : Top

1.7 : Bottom

1.8 : Perspective view 2

1.9 : Front view 2

1.10 : Back view 2

1.11 : Left view 2

1.12 : Right view 2

1.13 : Top view 2

1.14 : Bottom view 2

1.15 : Perspective view 3

1.16 : Front view 3

1.17 : Back view 3

1.18 : Left view 3

1.19 : Right view 3

1.20 : Top view 3

1.21 : Bottom view 3

The broken lines depict portions of the laundry sink with mini washing machine that form no part of the claimed design; reproduction **1.1** is a front perspective view of the laundry sink with mini washing machine; reproduction **1.8** is a front perspective view thereof in a condition that top sink cover has been opened; reproduction **1.15** is a front perspective view of reproduction **1.8** in a condition that the bottom drawer (mini washing machine cabinet) has been opened; reproductions **1.2**, **1.9** and **1.16** are front views of reproductions **1.1**, **1.8** and **1.15**, respectively; reproductions **1.3**, **1.10** and **1.17** are back views of reproductions **1.1**, **1.8** and **1.15**, respectively; reproductions **1.4**, **1.11** and **1.18** are
